UNITED STATES PATENT OFFICE

2,650,018

COMPRESSOR

Win W. Paget, Michigan City, Ind., assignor to
 Joy Manufacturing Company, a corporation of
 Pennsylvania

Application February 23, 1945, Serial No. 579,420

13 Claims. (Cl. 230—183)

1 My invention relates to pumps or compressors, and more particularly to compressors for air or other gaseous fluids.

It is sometimes necessary that compressors be built for compressing gaseous fluids to extremely high pressures. It is necessary with such compressors that every precaution be taken to prevent any leakage of oil into the compressor cylinders since the presence of oil in the compressed fluid may result in serious explosions taking place.

In a preferred form of my invention I have shown a compressor having four cylinders in which fluid is compressed in four stages. The two lower pressure cylinders are supported by guide members which are connected to a crankcase, and reciprocable within these pressure cylinders are pistons which are connected by piston rods to crossheads slidably supported by the guide members. By reason of the connection of the piston rods to the crossheads, the movements of the piston rods are such that means may be provided for sealingly engaging the piston rods to prevent the passing of oil along them to the cylinders. Such sealing means is provided, and, in order to prevent oil passing this sealing means from gaining access to the pressure ends of the cylinders, means are provided for draining oil from the lower ends of the pressure cylinders. The two higher pressure cylinders are supported at the outer ends of the lower pressure cylinders and the pistons in the higher pressure cylinders are connected for reciprocation with the pistons in the lower pressure cylinders. With this arrangement, the only fluid escaping along the pistons in the high pressure cylinders will be the fluid that is present in the compressor cylinders. To avoid the need for a supply of lubricant to the compressor cylinders, there are provided carbon liners for the compressor cylinders or carbon rings for the pistons. Instead of a compressor with four pressure cylinders, there may be provided, if desired, a compressor with more or less than four cylinders, and having two or more cylinders arranged in axial alignment.

An object of my invention is to provide an improved compressor for gaseous fluids. Another object is to provide an improved compressor which is capable of compressing fluid to extremely high pressures. Still another object is to provide an improved multistage compressor having an improved arrangement of compressor cylinders. Yet another object is to provide a compressor having its parts so arranged and constructed as to prevent lubricant, such as oil, from

2 gaining admission to the compressor cylinders. Still another object is to provide a compressor having improved means for removing lubricant from places where it may gain admission to the compression chambers. Other objects of the invention will appear in the course of the following description.

In the accompanying drawings there are shown for purposes of illustration two forms which my invention may assume in practice.

In these drawings:

Fig. 1 is a vertical cross-sectional view taken in planes including the longitudinal axes of the cylinders of a V-type compressor, and showing an intercooler having portions connected between different stages of compression, parts being shown in elevation to facilitate illustration.

Fig. 2 is an enlarged elevational view of the right-hand end of the intercooler shown in Fig. 1.

Fig. 3 is an elevational side view, with parts broken away, showing the end portion of the intercooler as viewed from the right in Fig. 2.

Fig. 4 is a cross-sectional view taken on the plane of the line 4—4 of Fig. 3.

Fig. 5 is a horizontal sectional view taken on the line 5—5 of Fig. 3.

Fig. 6 is an enlarged fragmentary sectional view taken on the plane of the line 6—6 of Fig. 1.

Fig. 7 is a vertical cross-sectional view of a compressor having its cylinders arranged in axial alignment and taken in planes including the longitudinal axes of the compressor cylinders.

Fig. 8 is a fragmentary horizontal sectional view taken on the plane of the line 8—8 of Fig. 7.

In the embodiment of my invention illustrated in Figs. 1 to 6, there is shown a multistage compressor 1 including a crankcase 2 having two cylindrical-shaped projecting portions 4 and 5 spaced angularly from each other. Connected to the outer end of the projecting portion 4, as by

40 screws 6, is an annular member 7 against which a flange portion 8 of a guide cylinder 9 rests. Engaging the flange portion 8 is a cylindrical-shaped spacing member 10 surrounding the guide cylinder 9 and supporting at its outer end a compressor cylinder 12. A flange portion 13 on the compressor cylinder engages the outer end of the spacing member, and this flange portion, the spacing member, and the flange portion 8 of the guide cylinder are secured, as by screws 15 to the annular member 7. The guide cylinder has a guideway 16 for reciprocably guiding a crosshead 17 which is connected by a connecting rod 18 to a crankshaft 19 extending through the crankcase 2 and driven by suitable power means, not shown. The crosshead is also connected to a

45

50

55

piston rod 20 which is attached to a piston 21 contained within the compressor cylinder 12 and carrying carbon rings 22 slidably engaging the cylinder walls. A packing ring 23 supported in an opening in an outer end wall of the guide cylinder sealingly engages the piston rod 20 and prevents the escape of lubricant from the crankcase to the compressor cylinder beneath the piston 21. The compressor cylinder 12 is the low pressure cylinder of the multistage compressor, the other compressor cylinders, in the order of increasing pressure ranges, being indicated by reference numerals 24, 26 and 28.

The compressor cylinder 24 has a flange portion 29 resting on a flange portion 30 of a guide member 31, and the flange portion 30 rests on the outer end of a crosshead guide 32 which abuts the projecting portion 5 of the crankcase. The cylinder 24, the guide member 31, and the crosshead guide 32 are arranged in axial alinement with each other and with the projecting portion 5 and are attached to the latter by screws 34. Reciprocable within the crosshead guide 32 is a crosshead 35 which is connected by a connecting rod 36 to the crankshaft 19. The crosshead 35 is also connected by a piston rod 38 to a piston 39 contained within the cylinder 24 and carrying carbon rings 40 slidably engaging the cylinder walls. Fixed to the member 31 in any suitable manner is an annular member 41 carrying oil rings 42 which engage the piston rod 38 for preventing the escape of oil along the latter to the cylinder 24.

Fixed to the outer ends of the compressor cylinders 12 and 24 respectively are head members 44 and 45. The head member 44 is provided with an intake chamber 46 which receives fluid, such as air, from an intake conduit 47 and is communicable, under the control of an inlet valve mechanism 48, with the interior of the compressor cylinder 12. Fluid is taken into the cylinder 12 past the inlet valve mechanism 48 during the suction stroke of the piston 21 and is then compressed and discharged past a discharge valve mechanism 50 to a discharge chamber 51 where it enters a conduit 52 and is conducted to an intercooler, generally designated 53.

The intercooler 53 includes head members 55 and 56, the head member 55 having, as shown in Fig. 4, chambers 57, 58 and 59, and the head member 56 having similar chambers, one of these being shown in Fig. 6. Conduits 60 connect each of the chambers 57, 58 and 59 in communication with the corresponding chamber (one is shown at 57') in the head member 56. Spaced along the conduits 60 are cooling fins 61 for dissipating heat from the conduits.

The conduit 52 is connected to the chamber 57, and fluid discharged through this conduit to the chamber 57 enters the conduits 60 opening thereto and is conducted to the corresponding chamber 57' in the head member 56. The fluid is then conducted from the latter chamber through a conduit 64 to an intake chamber 65 in the head member 45, and fluid conducted to this intake chamber is delivered, under the control of an inlet valve mechanism 66, to the compressor cylinder 24. The fluid is compressed further in the cylinder 24 and then discharged under the control of a discharge valve mechanism 67 to a discharge member 68 where it enters a conduit 69 and is conducted to the chamber 58 in the head member 55 of the intercooler. Fluid conducted to the chamber 58 enters the conduits 60 open-

ing thereinto and is conducted to the corresponding chamber in the head member 56. A conduit 71 conducts the fluid from the latter chamber to an intake chamber 72 formed in a head member 73 which is attached, as by screws 74, to the outer end of the compressor cylinder 26.

The compressor cylinder 26 is supported by the head member 44 in axial alinement with the compressor cylinder 12 and comprises a cylindrical casing 76 having a bore 77 in which a sleeve-shaped liner 78 is arranged. Reciprocable within the liner 78 is a piston 79 which projects at its inner end through an opening 80 in the head member 44 and is connected, as by welding, to a member 81 which is shown herein as being threaded to the outer end of the piston rod 20. Carried by the piston 79 are rings 82 slidably engaging the walls of the liner 78 and having a close fit with the latter so as to prevent the escape of fluid from the compressor cylinder 26 along the piston. The rings 82 are made of a metal such as steel or bronze so that they will expand to maintain a close fit with the liner as wear takes place, and the liner is made of a material such as carbon so that a supply of lubricant to the surfaces will not be needed.

Fluid delivered by the conduit 71 to the intake chamber 72 is admitted under the control of an inlet valve mechanism 84 to the compressor cylinder 26 where it is compressed still further by the piston 79 and then discharged past a discharge valve mechanism 85 to passages 86 opening through the head member 73 into a conduit 88 leading to the chamber 59 in the head member 55 of the intercooler. The fluid is conducted from the chamber 59 through the conduits 60 to the corresponding chamber in the head member 56 where it enters a conduit 90 and is conducted to an intake chamber 91 formed in a head member 92 which is connected to the outer end of the compressor cylinder 28.

The compressor cylinder 28 is attached to the head member 45 in axial alinement with the compressor cylinder 24 and comprises a casing 94 having a bore 95 in which a sleeve-shaped carbon liner 96 is received. Reciprocable within the liner 96 is a piston 97 which projects through an opening 98 in the head member 45 and is connected in any suitable manner to the outer end of the piston rod 38. Expansible rings 100, made of a metal such as steel or bronze, are carried by the piston 97 and slidably engage the walls of the liner 96 with a close fit so as to prevent the escape of compressed fluid along the piston. The presence of the carbon liner makes it unnecessary to supply a lubricant to this cylinder.

Fluid conducted to the intake chamber 91 by the conduit 90 is admitted to the cylinder 28 under the control of an inlet valve mechanism 102. The fluid is compressed still further in this cylinder by the piston 97 and is then discharged past a discharge valve mechanism 103 to passages 104 opening through the head member 92 into a conduit 106 which leads to a place of storage or to a point of use.

In order to prevent a variation of pressures in the compressor cylinder 12 beneath the piston 21 and to vent from this space any oil or water gaining admission thereto, the lower end of the cylinder 12 opens into the cylindrical-shaped spacing member 10, and the spacing member is provided with ports 108 opening through its side walls to atmosphere. The lower end of the compressor cylinder 24 is connected to atmosphere

5

through a port 110 so as to prevent a variation of pressure therein; and a conduit 112 is connected at one end in communication with a groove 114 formed in the cylinder wall between the ends of the latter, and is connected at its other end in communication with the intake conduit 41 for the low pressure cylinder 12. It will be seen that any fluid entering the groove 114 will pass through the conduit 112 into the intake to the low pressure cylinder. In order to reduce the tendency of lubricant to move along the piston rod 38 into the lower end of the compressor cylinder 24, a passage 115 in the guide member 31 connects the space surrounding the lower portion of this piston rod to a recess 116 in the cross-head guide 32, and a conduit 118 connects the recess to a point of low pressure, such as the intake manifold for the engine which may be used to drive the crankshaft 19.

There is shown in Figs. 7 and 8 a compressor like that of Fig. 1 except that the compressor cylinders extend in horizontal planes from opposite sides of a crankcase 120. The parts of this compressor corresponding to parts of the compressor shown in Fig. 1 have been given like reference numerals. The crankcase 120 has cylindrical projecting portions 121 and 122 at its opposite sides, these portions having their axes parallel to each other and lying in the same horizontal plane. The guide member 9, the spacing member 10, and the low pressure cylinder 12 are connected by the screws 15 to the crankcase portion 124 in axial alinement with the latter, and the crosshead guide 32, the guide member 31, and the pressure cylinder 24 are connected by the screws 34 to the crankcase portion 120 with their axes in alinement with the axis of this portion. The compressor cylinders 26 and 28 are connected, as in the first form of the invention, to the head members 44 and 45 at the outer ends of the pressure cylinders 12 and 24, respectively.

As a result of my invention there is provided an improved multistage compressor. With the arrangement of the compressor cylinders as shown, the means for sealing the compressor cylinders from communication with the crankcase, and the means for draining lubricant from the cylinders connected to the crankcase, the possibility that lubricant will gain admission to the compressor cylinders is reduced to a minimum.

While there are in this application specifically described two forms which the invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. In combination, in a pump, a cylinder, a piston reciprocable in said cylinder and having a piston rod, a crosshead secured to said piston rod, a crosshead guide having a tubular portion coaxial with said cylinder, said piston being hollow and having a skirt portion extending towards said crosshead, said tubular guide portion projecting into the hollow of said piston, means carried by said tubular guide portion and disposed within said piston in at least one extreme position of the latter for sealingly engaging said piston rod, and means for venting the space within said piston externally of said guide portion to atmosphere.

6

2. In combination, in a pump, a cylinder, a piston reciprocable in said cylinder and having a piston rod, means providing a sealed space through which said piston rod passes, and means for connecting said space to a source of sub-atmospheric pressure so that any lubricant flowing along said piston rod into said space is drawn off.

3. In combination, in a pump, a cylinder, a piston reciprocable in said cylinder and having a piston rod, means providing a chamber through which said piston rod passes and having seals at its opposite ends sealingly engaging said rod, said chamber receiving any lubricant flowing along said rod toward said cylinder, and means for connecting said chamber to a source of sub-atmospheric pressure so that any lubricant leaking past a seal into said chamber is drawn off.

4. In combination, in a pump, coaxial cylinders of different size and capacity in which fluid may be placed under relatively different pressures, a guide coaxial with said cylinders, pistons reciprocable in said cylinders respectively, a crosshead guided in said guide, the piston remote from said crosshead having a piston rod projecting into said inner cylinder and secured to said crosshead, said inner piston being secured to said piston rod between the outer piston and said crosshead, and means for detachably securing said inner piston to said piston rod, said inner piston being hollow and open at one end and said crosshead guide projecting into the hollow thereof so that said crosshead guide is disposed in part within said piston in at least one extreme position of the latter so that a transverse plane perpendicular to the axis of the piston rod cuts through both said inner piston and said crosshead.

5. In combination, in a pump, a cylinder, a piston reciprocable in said cylinder and having a piston rod, said piston being hollow and open at one end, means forming a septum for one end of the cylinder and projecting into the hollow of said piston at least in one extreme position of the latter to provide a sealed chamber surrounding said piston rod for receiving any leakage of lubricant along said piston rod toward said piston to prevent access of lubricant to said cylinder, and means for connecting said chamber to a source of sub-atmospheric pressure so that any lubricant leaking into said chamber is drawn off.

6. In combination, in a pump, a cylinder, a crosshead guide aligned with said cylinder, a crosshead guided in said guide, a piston reciprocable in said cylinder and having a piston rod secured to said crosshead, means carried by said guide and projecting into said cylinder and providing a sealed chamber surrounding said piston rod for intercepting flow of lubricant along said piston rod toward said cylinder, and means for connecting said chamber to a source of sub-atmospheric pressure so that any lubricant leaking into said chamber is drawn off.

7. In combination, in a pump, a cylinder, a piston reciprocable in said cylinder, said piston being hollow and open at one end, a crosshead guide aligned with and projecting into said cylinder with a portion thereof disposed in the hollow of said piston in at least one extreme position of the latter, and a crosshead reciprocably guided in said guide, said piston having a piston rod secured to said crosshead.

8. In combination, in a pump, a cylinder, a piston reciprocable in said cylinder and hollow

and open at one end, a crosshead guide, said piston moving in a path at one end of which said crosshead guide is at least partially within said piston, and a crosshead guided by said crosshead guide and fixed to said piston.

9. In a compressor, a cylinder, a crosshead guide, a piston reciprocable in the cylinder, a crosshead reciprocable in said guide, a piston rod secured to the crosshead and to the piston, means providing a chamber through which the piston rod passes, a seal at each end of the chamber and having fluid sealing engagement with the rod, and means to connect the chamber to a source of sub-atmospheric pressure, including passage means through said guide.

10. In a compressor, a crankcase, a cylinder, means to support the cylinder on the crankcase, a piston reciprocable in the cylinder, a piston rod connected to the piston, means providing a sealed space through which the piston rod passes, and means to connect said space to a source of sub-atmospheric pressure, including passage means through said support means.

11. The compressor of claim 10, in which the sealed space is a chamber mounted on said cylinder support means and having a rod-engaging seal at each end.

12. The compressor of claim 10, in which: the passage means includes a crosshead guide; a crosshead is reciprocably mounted in the crosshead guide; and the piston rod is also connected to the crosshead.

13. In a compressor, a casing member, a cross-

5
10

head guide mounted on the casing member, a cylinder, a hollow piston open at one end and reciprocable in the cylinder, a crosshead reciprocable in the crosshead guide, a rod connected to the crosshead and to the piston, means projecting into the open end of the piston in at least one extreme position thereof and providing a sealed space through which the rod passes, and passage means in said guide for connecting said space to a source of sub-atmospheric pressure to conduct lubricant collected in the space away from the cylinder.
